(57) CLAIM

The ornamental design for a laser module for firearm, as shown and described.

DESCRIPTION

FIG. 1 is a perspective view of a laser module for a firearm showing my new design.

FIG. 2 is a front view of the laser module.

FIG. 3 is a rear view of the laser module.

FIG. 4 is a left view of the laser module.

FIG. 5 is a right view of the laser module.

FIG. 6 is a top view of the laser module.

FIG. 7 is a bottom view of the laser module; and,

FIG. 8 is a perspective view of the laser module, showing of the laser module attached to the firearm.

The broken line portion of the figure drawings is included to show unclaimed subject matter only and forms no part of the claimed design.
